(57) **CLAIM**

The ornamental design for the guitar body, as shown and described.

DESCRIPTION

FIG. 1 is a perspective view of a guitar body showing our new design.

FIG. 2 is a front view thereof.

FIG. 3 is a rear view thereof;

FIG. 4 is a right-side view thereof;

FIG. 5 is a left-side view thereof;

FIG. 6 is a top view thereof;

FIG. 7 is a bottom perspective view thereof;

FIG. 8 is a front view thereof, showing the guitar body in the environment of a guitar; and,

FIG. 9 is a perspective view thereof.

The broken lines represent environmental structure, which forms no part of the claim, and the portions of guitar body that form no part of the claimed design.

1 Claim, 7 Drawing Sheets
